UNITED STATES PATENT OFFICE.

CHARLES WILLIAM SCHLEIER, OF CLEVELAND, OHIO.

LAUNDRY CABINET.

Application filed July 28, 1926. Serial No. 125,504.

This invention comprehends the provision of a new article of furniture, in the nature of a laundry cabinet designed to accommodate the necessary equipment for ironing clothes, a compartment for soiled clothes, and various compartments in which the ironed clothes can be kept.

In carrying out the invention the cabinet is provided with a compartment in which an ironing board and sleeve board is normally arranged and concealed from view, and capable of being readily and easily swung to a position for use, while normally arranged in the same compartment are pivoted bars also capable of being swung to projected positions to support the ironed clothes while the latter are drying.

Another object of the invention resides in the provision of a laundry cabinet including a hamper in which soiled clothes can be readily deposited, and a plurality of other compartments in which ironed clothes can be conveniently arranged and stored.

A further object of the invention resides in the provision of a cabinet of the class in question including a collapsible and adjustable seat which can be readily set up for use, occupying a position adjacent the ironing board when the latter is extended for use.

A still further object of the invention resides in the provision of a slide capable of being projected from the cabinet and upon which clothes are dampened prior to ironing the same, a water tank and sprayer being supported on the cabinet immediately above the slide.

Other objects and advantages will appear when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a perspective view showing the doors of the cabinet open to illustrate the arrangement of the compartments, and also illustrating the various parts extended for use.

Figure 2 is a sectional view through the cabinet and hamper, and also showing the ironing board and sleeve board extended for use as well as the clothes supporting rods.

Figure 3 is a horizontal fragmentary sec-

tional view through the cabinet showing the ironing and sleeve boards in plan and extended for use.

Referring to the drawings in detail, 10 indicates generally a cabinet which may be constructed from any suitable material, or metal, and which may also vary in size, including toy size, without departing from the spirit of the invention. The cabinet is divided by a vertical partition 11 and a horizontal partition 12 into compartments varying in dimensions. One of these compartments is indicated at 13 and is adapted to receive and house an ironing board 14, a sleeve board 15 and clothes supporting rods 16 when the latter are not in use, and to permit these parts to be conveniently swung outwardly to an extended position for use as clearly shown in Figure 1. Operating within the compartment 17 directly beneath the compartment 13 is a hamper 18 which is hinged at its lower end as at 19, and provided with a handle 20, so that the hamper can be conveniently opened and closed as the occasion may require. The hamper of course is arranged to receive soiled clothing. The compartment 21 opens at one end of the cabinet and has arranged therein a plurality of spaced shelves 22 upon which ironed clothing may be conveniently arranged, this compartment being normally closed by a door 23. Directly beneath the compartment 21 are arranged slidably mounted drawers 25 and 26 of different dimensions, these drawers being utilized to receive ironed linens and the like. While the compartment 21 opens at the end of the cabinet as above stated the compartment 13 opens at the front of the cabinet and is normally closed by a sliding door 27 as shown in Figure 1. This door is preferably provided with a mirrored surface 28.

By reason of the construction thus far described, it is manifest that by use of 100 the cabinet, the soiled clothes, the laundered clothes before being ironed, as well as the ironed clothes can all be conveniently arranged within the cabinet so that access may be had to the same at any time, and thus 105 overcome the objectionable present day custom of keeping such clothing in different parts of the house. In addition to having all the clothing arranged in a single cabinet for the convenience of the owner or user, all 110 of the equipment necessary for ironing the clothes, in addition to a seat upon which the

user may rest while using the ironing board, is so mounted on the cabinet as to be in an entirely out of the way position when not in use, and at the same time capable of being quickly extended for use when desired.

For the purpose of dampening or moistening the clothes prior to ironing the same I employ a slide 29 capable of being readily extended for use as shown in Figure 1. A water tank of any suitable capacity is indicated at 30, and is supported upon one of the shelves 22 in the compartment 21, and this tank is equipped with a faucet 31 from which extends a hose 32 carrying a sprayer head 33 on the lower end thereof. The sprayer and hose rest upon the slide 29 and can be conveniently used for the purpose above stated by simply opening the faucet 31.

The ironing board 14 is pivoted between the side walls of the compartment 13, on a transverse rod 15 and arranged on the under side of this board are spaced eyes 34 through which the legs 35 of a support therefor are mounted for sliding movement. The intermediate portion of this support is formed with a loop 36 arranged between the legs 35, and pivoted on this loop is a brace rod 37 having an offset extremity 38 adapted to engage a keeper 39 when used for bracing the support for the board as shown in Figure 1. When the support is arranged in the position just mentioned, the brace rod 37 is arranged at a right angle to the support to engage the keeper 39, whereby the board 14 is substantially supported for use.

The sleeve board 15 is mounted on a substantially U-shaped support indicated at 41, the latter being pivotally mounted within the compartment 13 directly behind the ironing board as indicated at 42. When the parts are normally arranged within the compartment, the sleeve board rests against the rear wall of the cabinet, while the ironing board rests against the support 41, and these boards can be singly swung outwardly to occupy the positions shown in Figure 1 when their use is desired. It will be noted that the support 41 for the sleeve board is slightly offset as at 43, so that when the sleeve board is extended for use the support 41 will lie flat upon the upper surface of the ironing board 14.

The clothes supporting rods 16 are nor-

mally arranged vertically within the compartment 13 and when swung outwardly to a horizontal position for use are arranged and supported in suitable brackets or keepers 44.

A stool or seat 45 is hingedly mounted on the front of the cabinet in any suitable manner as at 46, and this seat can be folded to lie against the front of the cabinet. The supporting structure 49 is mounted on casters or rollers 50 so that it can be moved outwardly from the cabinet, subsequent to swinging the seat 40 to a horizontal position for use. The supporting structure 49 for the seat includes spaced parallel rods 51 which slide in tubular guides 52 arranged on the under side of the cabinet, so that the supporting structure can be quickly and properly moved toward and away from the cabinet when it is desired to fold the seat, or extend the seat and support it in a position for use.

While it is believed that from the foregoing description, the nature and advantages of the invention will be readily apparent, I desire to have it understood that I do not limit myself to what is herein shown and described and that such changes may be resorted to when desired as fall within the scope of what is claimed.

What is claimed is:

In combination, a cabinet having a bottom wall and an opening in one side, a wall below said opening, a transverse rod upon said bottom wall, an ironing board pivoted adjacent its inner end on said rod and adapted to be arranged vertically within the cabinet when not in use and to be swung to a horizontal operative position outside of the cabinet, spaced supporting limbs pivoted on the under side of said board near the outer end thereof, the lower ends of said legs being adapted to engage the floor when the board is in operative position, said legs being formed at their lower ends with an upwardly directed medially disposed reentrant loop, a brace pivoted at one end to said loop and at its other end adapted to engage said wall, said brace and legs being adapted to fold into substantially parallelism with the board within the cabinet.

In testimony whereof I affix my signature.

CHARLES WILLIAM SCHLEIER.
